Primary Examiner — Jennifer Rivard*(74) Attorney, Agent, or Firm* — John M. Lipchitz(57) **CLAIM**

The ornamental design for a shaving razor cartridge, as shown and described.

DESCRIPTION

FIG. 1 is a perspective view of a shaving razor cartridge showing our new design;

FIG. 2 is a top view thereof;

FIG. 3 is a bottom view thereof;

FIG. 4 is a right view thereof;

FIG. 5 is a left view thereof;

FIG. 6 is a rear view thereof; and,

FIG. 7 is a front view thereof.

The broken lines shown illustrate portions of the shaving razor cartridge. The broken lines form no part of the claimed design. The dash-dot lines shown are boundary lines and form no part of the claimed design.
